[57] CLAIM

The ornamental design for an alignment device for mounting a dental model to a base cast, as shown and described.

DESCRIPTION

FIG. 1 is a perspective view of an alignment device for mounting a dental model to a base cast showing my new design;

FIG. 2 is a top plan view thereof;

FIG. 3 is a side elevational view thereof, the opposite side being a mirror image;

FIG. 4 is an end elevational view thereof, the other end being identical;

FIG. 5 is a bottom plan view thereof; and

FIG. 6 is a perspective view of a second embodiment thereof.
